SHIRT

Bernard S. Kulesa, 29 Alfred St., Rochester, N.Y.

Filed Aug. 25, 1965, Ser. No. 86,707

Term of patent 14 years

(Cl. D3—25)

FIG. 2

FIG. 1

FIG. 1 is a front elevational view of a shirt showing my new design;

FIG. 2 is a rear elevational view; and

FIG. 3 is an enlarged fragmentary view of a portion of the back of the shirt showing details of the letters and periods.

The characteristic features of my design reside in the chain stripe combined with the chain formed letters and ball and chain periods, the letters and periods being best shown in FIG. 3, and all as shown in full lines on the drawing.

I claim:

The ornamental design for a shirt, as shown and described.
